[57] CLAIM

The ornamental design for a egg cooking rack for a pan,
as shown and described.

DESCRIPTION

FIG. 1 is a perspective view of the egg cooking rack for
a pan with its carrier in the down position;

FIG. 2 is a front plan view thereof with its carrier in the
down position, the rear view being a mirror image;

FIG. 3 is a top plan view thereof;

FIG. 4 is a right side elevational view thereof with its
carrier in the down position;

FIG. 5 is a left side elevational view thereof with its
carrier in the down position;

FIG. 6 is a bottom plan view thereof;

FIG. 7 is a perspective view thereof with its carrier in
the up position; and,

FIG. 8 is a front plan view thereof with its carrier in the
up position, the rear view being a mirror image.
